UNITED STATES PATENT OFFICE

BENJAMIN J. SACHS, OF SPRINGFIELD, OHIO

GARMENT PROTECTOR

Application filed August 24, 1927. Serial No. 215,244.

My invention relates to garment hangers, and more particularly to a protector and spreader for engagement with the conventional wire hanger to prevent close folding and creasing of garments suspended thereon.

Because of their low cost a wire garment hanger is extensively used by dry cleaners, pressers, and clothing merchants upon which to suspend their finished work. Such conventional hangers consist of a length of rather small gauge wire bent to triangular form with its ends twisted together at the apex of the triangle and bent into a hook. Garments which are suspended upon cross member or bottom portion of such triangular hanger fold closely over the wire or cross member due to the weight of the garment and unsightly wrinkles or creases are produced, which are highly objectionable, especially in trousers or skirts which are ordinarily so suspended upon the hanger.

To overcome this difficulty there is provided in the present instance a spreader or protector to be suspended upon the cross member of the hanger and which will hold the garment distended forming a broad round supporting surface in lieu of the comparatively thin wire. This spreader or protector comprises an elongated section of sheet material, preferably though not necessarily, cardboard, which is bent upon itself into an inverted channel shape. The section is provided with integral end flaps which are folded transversely across the bent portion of the spreader or protector and beneath the wire hanger which extends within the channel of such spreader or protector. Such end flaps are formed with locking tongues engaging in suitable slots in the main portion of the spreader to secure the section of flexible material in its bent form. The inherent tension of the sheet material causes it to spread to greater extent through the medial portion than at the contracted and locked ends. This gives to the spreader or protector a somewhat inverted boat shape. In addition to the locking engagement of the end flaps beneath the wire hanger the main portion of the device is provided with terminal

tongues notched to receive the lower angles or bends of the hanger frame.

The object of the invention is to provide a hanger for garments affording a broad rounded supporting surface which will prevent the close folding and creasing of a suspended garment and particularly to provide such a protector or spreader engageable with the commercial type of wire garment hanger.

A further object of the invention is to provide a spreader or protector which will be cheapened in construction, efficient in operation, easily and quickly applied to a conventional form of wire hanger, capable of long periods of usefulness and unlikely to become injured or broken.

A further object of the invention is to provide improved means for securing such spreader or protector to the wire hanger, and to further provide ample surface for carrying advertising matter.

With the above primary and other incidental objects in view, as will more fully appear in the specification, the invention consists of the features of construction, the parts and combinations thereof, and the mode of operation, or their equivalents, as hereinafter described and set forth in the claims.

Referring to the drawings, Fig. 1 is a perspective view of a commercial type of wire garment hanger to which the present garment protector or spreader has been applied. Fig. 2 is a transverse sectional view of the protector or spreader engaged with the hanger and showing a garment suspended thereon. Fig. 3 is a detail perspective view of one end of the protector or spreader viewed from below. Fig. 4 is a plan view of the blank of flexible material from which the protector or spreader is formed.

Like parts are indicated by similar characters of reference throughout the several views.

While the present invention has been illustrated and will be described in its application to a conventional commercial type of wire garment hanger it is to be understood that it is not limited to such application but may be applied to other forms of garment hangers, one of the popular types of which is a

wooden hanger having a round wooden rod extending transversely at the bottom of the hanger, over which is suspended garments, such as trousers and skirts. This wooden rod, although of somewhat greater diameter than the wire of the commercial wire hangers is almost equally as objectionable, since it also allows the garment to fold closely, thus becoming creased or wrinkled. It is to be understood that the hanger per se forms no part of the present invention, but the device is equally applicable to different forms of garment hangers and may also be employed upon a wire or line.

It is not unusual in cleaning and pressing establishments to employ a wire or line stretched across the room on which to suspend garments. The present spreader or protector may be engaged with such clothes line or wire with equal facility and will serve the same purpose of preventing close folding and creasing of the garments.

Referring to the drawings, 1 is the commercial wire garment hanger having at its bottom a transverse or cross member 2. The protector or spreader forming the subject matter hereof comprises a section 3 of flexible sheet material bent into inverted channel shape and suspended over the cross member 2 of the hanger 1. The preferable material, because of its cheapness and ease of manipulation, is cardboard or manila tag board, although other materials, such as fiber, impregnated or stiffened fabric or even sheet metal may be employed. The hanger protector or spreader is provided with terminal heads or flaps 4 formed integral with the main section 3, and folded transversely beneath the cross member 2 of the hanger to close the ends of the channel shaped bent body 3. These terminal heads 4 each carry a locking tongue 5 engageable in a slot 6 suitably located in the side of the channel shaped bent body 3 to retain the body in its adjusted bent position. The main portion 3 is provided with projecting tongues at its opposite ends, notched at 7 to receive the stems or base angles of the wire hanger 1. The top margins of the terminal flaps 4 are also preferably notched at 8 to accommodate the cross member 2 of the hanger 1. The spreader or protector, although limited to the width of the terminal head or end flap 4 at its extremities, spreads considerably wider than at such terminal heads at its medial portion, due to the inherent tension of the sheet material. This gives to the protector or spreader convex or bowed bottom margins which not only tends to further spread the garments suspended upon such spreader or protector and through the wire hanger 1, but it also serves to distend the lapels of a coat suspended upon the inclined upper portions of the hanger 1.

In Fig. 4 there is shown a plan view of the blank as cut and scored preparatory to being

bent and interlocked into the desired shape. This blank discloses an elongated substantially rectangular main portion, which when bent upon itself forms the inverted channel or boat shaped main body 3. Attached to the opposite ends of this elongated main portion by score or fold lines are the terminal flaps 4-4 which when folded transversely become the heads or ends of the device. Contiguous thereto are short offsets having therein marginal notches which in the finished product become the projecting tongues 6 with the marginal notches 7 for engagement of the hanger 1. The locking flaps project in opposite directions beyond the end flaps 4 to which they are integrally joined on fold or score lines indicated by dotted lines in Fig. 4.

From the above description it will be apparent that there is thus provided a construction of the character described, possessing the particular features of advantage before enumerated as desirable, but which obviously is susceptible of modification in its form, proportions, and arrangement of parts, without departing from the principle involved or sacrificing any of its advantages.

While in order to comply with the statute the invention is described in language more or less specific as to structural features it is to be understood that the invention is not limited to the specific details shown, but that the means and construction herein disclosed comprise the preferred form of several modes of putting the invention into effect, and the invention is therefore claimed in any of its forms or modifications within the legitimate and valid scope of the appended claims.

Having thus described my invention I claim:

1. As an article of manufacture, a garment spreader comprising an inverted channel shaped member of sheet material having a rounded cross sectional contour, and terminal spreader heads in said member, a conventional wire garment hanger being engageable within said inverted channel member which encloses the cross member of the hanger to prevent close folding and creasing of a garment suspended thereon.

2. As an article of manufacture, a garment spreader comprising a sheet of flexible material including a main section to be reversed upon itself to rounded channel shape, an integral head section at each end of the main section foldable to transverse position relative to the reversed main portion, and a tongue attached to the free margin of each head section for engagement in a suitably located slot in the main portion to hold said spreader in assembled relation, the spreader being engageable with the cross member of a garment hanger to prevent close folding and creasing of a garment suspended thereon.

3. A garment spreader comprising an elongated portion of flexible sheet material to be

5 bent upon itself into tensioned inverted rounded channel shape for suspension over the cross member of a garment hanger, and means for maintaining the portion of material in its bent form, and notched tongues projecting from the opposite ends thereof in the notches of which the garment hanger is engageable.

10 4. A garment spreader comprising an elongated portion of flexible sheet material to be bent upon itself into tensioned inverted rounded channel shape for suspension over the cross member of a garment hanger, means for maintaining the portion of material in its bent form, and end flaps carried thereby engageable beneath the cross member of the hanger over which the bent portion is suspended.

15 5. A garment spreader comprising an elongated portion of flexible sheet material to be bent upon itself into tensioned inverted rounded channel shape for suspension over the cross member of a garment hanger, and flaps carried thereby engageable beneath the cross member of the hanger upon which the bent portion is suspended, and terminal tongues on said bent portion overhanging the end flaps.

20 6. A garment spreader comprising an elongated portion of flexible sheet material to be bent upon itself into inverted rounded channel shape for suspension over the cross member of a garment hanger, said bent portion having terminal notches therein for engagement with the garment hanger, and flaps carried by the bent portion to be transversely disposed in assembly of the spreader, also notched for engagement with the hanger.

25 In testimony whereof, I have hereunto set my hand this 18th day of August, A. D. 1927.
40 BENJAMIN J. SACHS.
